UNITED STATES PATENT OFFICE.

ENÉAS GEUINARÆS MASCARENHAS, OF JUIZ DE FORA, BRAZIL.

ELECTRIC LAMP.

1,421,276.

Specification of Letters Patent. Patented June 27, 1922.

Application filed September 5, 1919. Serial No. 321,833.

To all whom it may concern:

Be it known that I, ENÉAS G. MASCARENHAS, a citizen of the Republic of Brazil, and a resident of Juiz de Fora, Estado de Minas, 5 Brazil, South America, have invented a new and Improved Electric Lamp, of which the following is a full, clear, and exact description.

This invention relates to electric lamps, 10 sometimes called glow lamps, and has for an object to provide an improved arrangement whereby by proper adjustment more than one filament may be used in the same globe.

15 Another object of the invention is to provide an incandescent electric lamp in which a number of filaments are provided and associated with a switch mechanism at the base of the lamp in order that any of the 20 filaments may be connected up with a source of current when the lamp is in use.

In the accompanying drawing:

Figure 1 is a view of a lamp embodying the invention, shown partially in elevation 25 and partially in section.

Figure 2 is a section through Figure 1 on line 2—2.

Figure 3 is a bottom plan view of the lamp shown in Figure 1.

30 Figure 4 is a view similar to Figure 2, but showing a slightly modified form of the invention.

Figure 5 is a view similar to Figure 1, but showing a modified arrangement wherein 35 one of the return wires is connected directly to the center contact.

Figure 6 is a bottom plan view showing the arrangement of contact structure illustrated in Figure 5.

40 Referring to the accompanying drawing by numerals, 1 indicates a globe which is provided with a base 2 of any usual construction for fitting in any desired socket. This base is provided with the usual contact 45 3 which is insulated from the metal shell engaging the socket in the usual manner so that the base 3 may be connected to either of the leading-in wires 4 and 5. This connection is through a switch 6 rotatably mounted 50 on the contact 3 and provided with an arm 7 adapted to engage the ends 8 and 9 of the leading-in wires 4 and 5. Preferably the switch 9 fits rather snugly the contact 3 so that there will be always a good electrical 55 connection. The base 2 supports a glass standard or tree 10 having what may be

termed a head 11 which is designed to carry supporting members 12 which may be of wire, or other desired material. The standard 10 also may be made of other material 60 beside glass, though glass is preferable by reason of its convenience in manufacture and arrangement in the bulb or globe 1. The supporting members 12 are connected in any suitable manner to the filaments 13 and 14 65 as shown in Figure 2, while the leading-in wires 4 and 5 are electrically connected to the ends of these filaments, and a common return wire 15 is connected to the opposite end of the filaments 13 and 14 engaging the 70 wires 4 and 5. In the drawing the filaments 13 and 14 are shown as a single member, which may be the case, or they may be separate and individually connected to the common return 15. 75

In Figures 1, 2 and 3 the lamp is shown as having two filaments, but it is to be understood that any number of filaments could be used having equal lighting power and capable of receiving the same current, or 80 arranged to receive the same current, but with different lighting powers, as for instance the construction shown in Figure 4.

In Figure 4 a slight modified form of the invention is shown in which the same arrangement is illustrated as shown in Figure 2, except that two additional filaments 13' and 14' are provided so that by a proper operation of the switch 6 any one of the four may be used. As above mentioned any 90 number of filaments may be used and connected to what is termed a common return and to independent leading-in wires. Preferably all of these filaments are capable of receiving the same voltage and the same 95 amperage, though if desired the filaments could be varied for any particular purpose desired. In using the lamp the arm 7 is placed on one of the leading-in wires and then the lamp screwed into a suitable socket. 100 As soon as it has been properly screwed into the socket and the switch of the socket turned on current will flow through contact 3 to the switch 6 and from thence through arm 7, end 8, leading-in wire 4 to filament 105 13 and from thence through the return wire 15 and base 2 to the source of current. Current will continue to flow in this manner until the switch 6 is changed or until the filament 13 has burned out. Whenever filament 13 burns out, or is broken through any 110 cause the lamp is removed and the arm 7

shifted to the end of another leading-in wire and the lamp again placed in its socket. When shifted to the end of leading-in wire 5 current will be supplied to the filament 14 which will give the desired illumination. If there are additional filaments as shown in Figure 4 the switch may be additionally shifted from time to time until all the filaments have been used or until the deposit 10 on the interior surface of the globe 1 has made the lamp unserviceable. Where there is a chemical provided in the bulb for preventing a deposit on the globe 1 a large number of filaments may be used in one 15 bulb.

Referring to Figures 5 and 6, a further modified form of the invention is shown wherein the central lead-in wire 15' is connected with contact 3 while the remaining 20 lead-in wires are provided with suitable contacts 16, 17 and 18 connected to suitable filaments, as for instance the filaments 13, 13', 14 and 14', shown in Figure 4. By this construction and arrangement the arm 7 is 25 left out of engagement with any of the contacts 16 to 18 when the lamp is first screwed into the socket. This will cause current to pass through the central contact 3, lead-in wire 15' to one of the filaments, through 30 said filament and out the wire 15 to the sleeve 2 and from thence back to the source. It is, of course, understood that the return wire 15 is used in connection with the structure shown in Figure 5. When the first 35 filament has burned out the lamp is removed and the arm 7 moved to one of the contacts 16, 17 or 18 and is then inserted into its socket. When the second filament has

burned out the lamp is removed and the arm moved to another contact, and so on until 40 all the filaments have burned out. The arrangement shown in Figure 6 will accommodate four filaments as illustrated in Figure 4, but the same arrangement may be used for a larger number of filaments, or 45 even a less number.

What I claim is:

1. In an electric incandescent lamp a globe, a base, a standard carried by the base and projecting into the globe, a plurality 50 of arc-shaped filaments arranged in the same plane, contiguous to each other in a plane at right angles to said standard, said filaments being also arranged eccentrically to each other and a plurality of lead-in wires 55 connected with said filaments, one of said lead-in wires being connected to all of the filaments and acting as a common return while the other lead-in wires are connected to individual filaments whereby any filament may be used independently. 60

2. In an incandescent electric lamp a globe, a base, a standard carried by the base and projecting into the globe, a plurality 65 of open ring filaments arranged in the same plane and at right angles to the standard, said filaments being contiguous for substantially the full length and a plurality of lead-in wires connected with said filaments, one of said lead-in wires being connected to 70 all of the filaments and acting as a common return while the other lead-in wires are connected to individual filaments, said common return wire acting to divide each of said filaments into two arc-shaped sections. 75

ENÉAS GEUINARAS MASCARENHAS.
